United States Patent Office.

ISAAC M. ROSS, OF PETERSBURG, INDIANA.

Letters Patent No. 96,483, dated November 2, 1869.

APPARATUS FOR TURNING THE LEAVES OF MUSIC.

The Schedule referred to in these Letters Patent and making part of the same.

To all whom it may concern:

Be it known that I, ISAAC M. ROSS, of Petersburg, in the county of Pike, and in the State of Indiana, have invented certain new and useful Improvements in Devices for Turning the Leaves of Music; and do hereby declare that the following is a full, clear, and exact description thereof, reference being had to the accompanying drawings, and to the letters of reference marked thereon, making a part of this specification.

The nature of my invention consists in the construction and general arrangement of a device for turning the leaves of music without interrupting the playing.

In order to enable others skilled in the art to which my invention appertains, to make and use the same, I will now proceed to describe its construction and operation, referring to the annexed drawings, in which—

Figure 1 is a plan view of the entire apparatus;

Figure 2 is a bottom view of the upper portion; and

Figure 3 is a bottom view of the lower portion of the apparatus.

A represents a frame, of suitable dimensions, to be secured to, or made in connection with the music-rack.

In the upper portion of the frame A is a place for the music to stand, and be held in the centre by the rod *a*.

Below this place for the music, within the frame A, is a concave slide, B, having a zigzag groove formed on it.

On a rod above this slide is placed a series of rollers, C C, each of which is provided with an arm, D, to which the music is secured by means of springs, or other simple means.

The rollers C C have, also, each a projection, *i*, opposite the arm D, which is to connect with the slide B, by passing through the zigzag groove therein, and gives motion to the arms as the slide passes up and down.

E represents a plate or frame, with pulleys and projecting parts, suitable to be screwed to the floor, said plate or frame having a notched groove in it, as seen in figs. 1 and 3, by means of which a slide, F, is regulated, so that its motion will correspond with the motion required to turn one of the arms D D.

The apparatus is operated by having a cord or belt passing, from the slide F, to which it is secured, through pulleys suitably arranged to the concave slide B, and back to the slide F, where it is again secured, so that, by moving the slide F with the foot the distance of one notch in the groove of the frame E, the slide B will be moved sufficient to turn one of the rollers C, and, consequently, that sheet which is attached to its arm.

The plate or frame E may be secured, in a suitable manner, near the key-board, so as to be operated by the hand, instead of with the foot.

Having thus fully described my invention, What I claim as new, and desire to secure by Letters Patent, is—

1. The concave slide B, provided with a zigzag groove, for the purpose of operating the rollers C C, substantially as herein set forth.

2. In combination with the concave slide B, the rollers C C, having arms D D and projections *i*, all constructed as described, and operating within the frame A, substantially as and for the purposes herein set forth.

3. The combination of the frame A, grooved concave slide B, rollers C C, arms D D, frame E, having a notched groove, and the slide F, all constructed and connected as described, and operating substantially in the manner and for the purposes herein set forth.

In testimony that I claim the foregoing, I have hereunto set my hand, this 13th day of August, 1869.

ISAAC M. ROSS.
